Harry L. Finger.

UNITED STATES PATENT OFFICE

144,607

DESIGN FOR A DENTAL STIMULATING INSTRUMENT

William J. Charters, Ankeny, Iowa

Application July 7, 1945, Serial No. 120,555

Term of patent 14 years

(Cl. D24—1)

To all whom it may concern:

Be it known that I, William J. Charters, a citizen of the United States, residing at Ankeny, in the county of Polk, and State of Iowa, have invented a new, original, and ornamental Design for a Dental Stimulating Instrument, of which the following is a specification, reference being had to the accompanying drawing, forming part thereof:

Figure 1 is a top plan view of the dental stimulating instrument showing my new design;

Figure 2 is a side elevational view of the dental stimulating instrument shown in Figure 1; and

Figure 3 is a view similar to Figure 2 but with the stimulating member omitted and the lock nut screwed partly back.

I claim:

The ornamental design for a dental stimulating instrument, substantially as shown.

WILLIAM J. CHARTERS.
